UNITED STATES PATENT OFFICE.

HUGHT ALEXANDER GRANT, OF MALONE, NEW YORK.

REFRIGERATOR.

Application filed April 7, 1924. Serial No. 704,807.

To all whom it may concern:

Be it known that I, HUGHT ALEXANDER GRANT, a subject of the King of Great Britain, residing at Malone, in the county of 5 Franklin and State of New York, have invented a new and useful Refrigerator, of which the following is a specification.

This invention relates to refrigerating or cooling chambers.

10 The object of the invention is to provide a simply constructed refrigerator in which a maximum cooling effect will be produced with a minimum consumption of ice.

15 With the foregoing and other objects in view which will appear as the description proceeds, the invention resides in the combination and arrangement of parts and in the details of construction hereinafter described and claimed, it being understood 20 that changes in the precise embodiment of the invention herein disclosed, may be made within the scope of what is claimed without departing from the spirit of the invention.

25 In the accompanying drawings:—

Figure 1 represents a vertical section taken on the line 1—1 of Fig. 3.

Fig. 2 is a horizontal section taken on the line 2—2 of Fig. 1.

30 Fig. 3 is a vertical section taken in a plane at right angles to Fig. 1 on the line 3—3 of Fig. 1.

Fig. 4 is a detail of one of the supporting standards of the removal boards in front of the ice compartment.

35 Fig. 5 is a detail perspective view of the air deflector; and

Fig. 6 is a similar view of the drip pan.

In the embodiment illustrated a chamber 1 is shown having the walls thereof provided 40 with dead air spaces 2 to insulate the contents of the chamber. The floor of this chamber is here shown made of cement 3.

Mounted within the chamber 1 is an ice container 10 in form of a rack 11 with a drip pan 12 arranged below it. This drip pan 12 is provided with an upstanding flange around it and in the bottom thereof has a screened opening 13 from which a drain pipe 14 leads.

45 Rising from the front of rack 11 at the corners thereof are two angle iron standards 15 equipped with seats 16 to support removable boards 18 which are arranged one above the other as shown in Fig. 3 and held in op-

erative position by keepers or lugs 17 which 55 form stops to prevent the boards falling inward against the ice. These boards 18 are made removable to facilitate the insertion of ice on the rack so that any desired quantity of ice may be placed on the rack and held in 60 operative position by the boards, the ice being shown in Fig. 3 by dot and dash lines as indicated at I.

Between the front wall of the ice and the boards 18 is formed a space 19 for the passage of air between said boards and the ice the air entering at the top and passing down against the ice and cooled leaving the ice compartment through the opening 25 at the lower portion of which is arranged a downwardly inclined air deflector 20. This deflector 20 extends into the ice compartment 70 so that the air impinging thereagainst is directed downwardly into the chamber 1 and rises up to the top of said chamber passing 75 again into the ice container in the manner above described.

The deflector 20 is preferably constructed as shown in Fig. 5 with a downturned right angular flange 21 at its rear wall provided 80 with an inwardly extending apertured lip 22 which forms an attachment for securing the deflector to the rack 11.

Arranged across the front of the ice container outside the boards 18 are a plurality 85 of vertically spaced transversely extending bars 23 which are equipped with hooks 24 on which are designed to be suspended meats or other articles to be cooled.

In the use of this refrigerator the hot or 90 warm air entering the top of the ice compartment impinges against the ice at the upper portion thereof thus causing it to melt along the dotted line shown at 26 the air getting cooler and cooler as it descends and 95 finally when it passes out through the opening 25 is sufficiently cooled for the purpose desired and enters the chamber 1 where it contacts with the object or articles therein to be refrigerated.

As the cakes of ice melt at the top of the compartment the top or uppermost board 18 is removed to permit the air to pass over the next adjacent in contact with the ice for the purpose above set forth.

100 This refrigerator is very simple and easy to construct and will be equally as efficient as the more expensive ones.

I claim:—

1. A refrigerator comprising a cooling chamber having an ice rack supported therein, an ice shield positioned above and in front of said rack and terminating at its lower end at a point above the rack and at its upper end at a point spaced from the ceiling of said chamber with an air space or passage formed between the shield and the ice, and a downwardly inclined air deflector located within and spaced from said shield to direct the cold air toward the floor of the cooling chamber, said shield being formed in detachable sections.
2. The combination with a cooling chamber having an ice rack mounted therein with a drip pan located beneath said rack, a plurality of boards superposed edgewise one above the other in front of said rack and removably mounted, forming a sectional ice shield, the lowermost board being spaced above the rack, a cold air deflector located below said board and extending in planes on

opposite sides thereof, said deflector being inclined downwardly toward the front 25 thereof.

3. The combination with a cooling chamber having an ice rack mounted therein above the floor thereof, standards rising from the front corners of said rack, said standards being composed of angle iron one member of which has inwardly projecting stops, each of said standards having a seat formed therein, boards mounted edgewise in said standards and resting on said seats, said stops operating to hold the boards against inward movement, and a space formed between said seats and the rack to provide an outlet for the cold air from the ice chamber.

In testimony that I claim the foregoing as 40 my own, I have hereto affixed my signature in the presence of two witnesses.

HUGHT ALEXANDER GRANT.

Witnesses:

MARGARET GRANT,
JAMES ALEXANDER GRANT.
